UNITED STATES PATENT OFFICE.

JAMES EDWARD ROBINS AND WILLIAM STALLWOOD SLACK, OF HAGERSVILLE,
ONTARIO, CANADA.

DIAPHRAGM FOR SOUND BOXES.

1,419,943.

Specification of Letters Patent. Patented June 20, 1922.

Application filed December 1, 1920. Serial No. 427,514.

To all whom it may concern:

Be it known that we, JAMES EDWARD ROBINS and WILLIAM STALLWOOD SLACK, of the town of Hagersville, in the county of 5 Haldimand and Province of Ontario, Dominion of Canada, have invented certain new and useful Improvements in Diaphragms for Sound Boxes; and we hereby declare that the following is a full, clear, and exact description 10 of the same.

This invention relates to diaphragms for phonographs, made from the untanned dressed abdominal walls of bovidæ, technically known by the English term "abdominal tunic" and the Latin term "tunica flava abdominis," the object of the invention being to so prepare the material for these discs that they will correctly reproduce the sounds with the same tonal effect as the original 20 sounds.

Heretofore in the reproduction of sounds by phonographs and the like, the tonal effects of the instruments have been marred by the inability of the diaphragms, owing to 25 the material from which they have been made, to accurately reproduce the correct pitch and exact number of vibrations of the original sounds.

The object of the present invention is to 30 overcome these defects, this object being attained as hereinafter set forth and particularly pointed out in the claims.

In the drawings:

Fig. 1, is a plan view, and 35 Fig. 2, is a side elevation of a diaphragm made in accordance with this invention.

In carrying out the invention the abdominal tunic, i. e., the tunica flava abdominis of a bovine, is thoroughly cleaned of all fatty 40 substances and flesh and then stretched and dried, by any usual or approved method suitable for this purpose.

This untanned dressed material is then ground to a proper thickness, preferably by 45 means of fine sand paper or emery cloth,

and rendered proof against climatic changes by a coat of commercial gold size japan dryer rubbed in by hand.

When this material is properly prepared each diaphragm disc will respond uniformly 50 to all vibrations of the stylus, and equally distribute the sound waves over its entire surface, thereby producing the natural tones of the original sounds with a resonance which is not only mellow and voluminous, but also 55 entirely free from those impairments common to metallic and wooden diaphragms.

While we prefer to use the abdominal walls of bovidæ, we wish it to be understood that we do not desire the invention confined 60 to membranous material taken from these animals, nor do we wish to be confined to the use of gold size japan dryer as the sizing composition.

Having thus fully described my invention, 65 what I claim as new and desire to secure by Letters Patent is:

1. A diaphragm for sound reproducing instruments composed of the abdominal tunic of a bovine. 70

2. A diaphragm for sound reproducing instruments composed of the untanned dressed abdominal tunic of a bovine.

3. A diaphragm for sound reproducing instruments composed of the abdominal 75 tunic of a bovine which has been cleaned of fatty substances and flesh and then stretched and dried.

4. A diaphragm for sound reproducing instruments composed of the abdominal tunic 80 of a bovine from which has been removed all fatty substances and flesh and which has been thoroughly stretched, dried and ground to the desired thickness.

Toronto, Ontario, November 20th, 1920. 85

JAMES EDWARD ROBINS.

WILLIAM STALLWOOD SLACK.

Signed in the presence of—

DANIEL CARTER,

CHAS. H. RICHES.
